HAIR CURLER

Ruth K. Weaver and Paul T. Hahn, Chicago, Ill.,
assignors to Gaylord Products, Incorporated,
Chicago, Ill., a corporation of Delaware

Application August 19, 1950, Serial No. 180,470

4 Claims. (Cl. 132—40)

1

This invention relates to hair curlers, and is more particularly concerned with the provision of a hair curler adapted for use in forming pin curls.

In the hair dressing art the term "pin curl" is applied to a relatively small lock of hair wound into spiral form and secured in a flat condition against the scalp by means of hair pins or clips, the axis of the curl being disposed in a plane normal to the scalp. In the permanent waving of hair by means of a cold wave solution, it has heretofore been the practice of beauty operators to first saturate a lock of hair with the cold wave solution and then wind the saturated lock of hair about a curler having its axis parallel to the scalp. A neutralizing solution was then applied to the lock of hair on the curler, then the curl was removed from the curler and rinsed in clear warm water to remove the cold wave solution and neutralizer. The beauty operator then arranged the wet lock of hair into the form of pin curls and secured the curls in position by means of hair pins or clips until dry.

The present invention contemplates the provision of a hair curler adapted to eliminate the operation of forming and securing pin curls after the cold wave solution and neutralizer have been rinsed from the hair to thus effect a saving in time and labor.

It is a further object of this invention to provide a curler on which a lock of hair may be wound, waved, neutralized, rinsed and dried to form a pin curl.

It is another object of this invention to provide a curler on which a lock of hair may be wound either from the scalp end toward the free end or from the free end toward the scalp end.

It is another object of this invention to provide a hair curler adapted to be inexpensively formed from plastic, rubber or metal and applied to the hair of the user with or without the assistance of a beauty operator.

In a copending application, Serial No. 173,184, filed July 11, 1950, we have disclosed a hair curler adapted for use in forming pin curls, the curler comprising a body to receive a wound lock of hair and a retainer cap to hold the hair on the body. In the present invention, the curler body and retainer are formed to permit the waving solution, neutralizer and rinse water to more readily penetrate and saturate the curl, and the retainer serves to hold the curler body in position against the scalp.

This invention embodies other novel features, details of construction and arrangement of parts which are hereinafter set forth in the specifica-

2

tion and claims, and illustrated in the accompanying drawing, wherein:

Fig. 1 is an end elevational view illustrating a hair curler embodying features of the present invention.

Fig. 2 is a side elevational view of same.

Fig. 3 is a sectional view taken along the line 3—3 of Fig. 1.

Fig. 4 is a sectional view taken along the line 10 4—4 of Fig. 1.

Fig. 5 is a side elevational view showing the resilient hair retaining clip.

Fig. 6 is a front elevational view of the same.

Referring now to the drawing for a better understanding of this invention, the hair curler is shown as comprising a body 6 which is preferably formed of two sections 7 and 8 cemented together, the body section 7 embodying a plurality of arms 9 radially disposed about a hub 11, and the section 8 having a plurality of arms 12 radially disposed about a collar 13. The hub 11 is formed with a cylindrical boss 14 terminating at an abutment shoulder 15 for snug cemented engagement with the collar 13. The arms 9 are preferably located in registry with the arms 12 to define a plurality of V-shaped recesses 16 to receive a wound lock of hair, the inner ends of the two sets of arms being formed to define a plurality of grooves 17 extending at spaced intervals along the hub 11 and collar 13. The several arms 9 and 12 are formed with apertures 18 which extend inwardly for registry with grooves 19 extending at spaced intervals along the hub 11 and collar 13 between the grooves 17. Recesses 21 and 22 are formed in the ends of the hub 11 to receive offset portions 29 and 31 formed on a retaining clip 25.

The retaining clip 25 is shown as preferably comprising a piece of resilient stainless steel wire bent intermediate its ends to provide three acute concentric sections *a*, *b*, and *c*, the sections *a* and *b* being connected at *d* and the sections *b* and *c* being joined at *e*, to define a U-shaped clip portion 26, as viewed in end elevation in Fig. 1, to enclose a lock of hair wound about the curler body 6, the end portions of the wire being disposed in a common plane between the legs of the U-shaped clip portion to define a pair of resilient clamping fingers 27 and 28. The fingers 27 and 28 are formed with offset portions 29 and 31, respectively, for detachable engagement within the recesses 21 and 22 formed in the hub 11 of the curler body 6. The end portions of the fingers 27 and 28 are preferably flattened and bent away from each other at 32 and 33, respec-

tively, to define therebetween an inwardly converging recess, as viewed in side elevation, to receive the curler body 6.

In the use of the hair curler for making pin curls, a lock of hair is wound around the curler body 6 with the axis of the curl disposed in a plane normal to the scalp and with either end of the curler body in engagement against the scalp. It will be noted that a lock of hair may be wound on the curler body by starting the winding operation from either the scalp end or the free end of the hair. The curl is then secured within the recesses 16 of the curler body 6 by engaging the clip portion 26 of the retainer clip 25 around the curl and mounting the offset portions 29 and 31 of the fingers 27 and 28 within the recesses 21 and 22 formed in the hub 11 of the curler body. During mounting of the retainer clip upon the curler body, it will be noted that one of the fingers 32 or 33 will be inserted through the hair adjacent the scalp and thus serves to secure the curler body in its proper position. After a lock of hair has been wound around and secured in position upon the curler body, it is first saturated with a cold wave solution, then saturated with a neutralizer, then rinsed with clear warm water and dried, and then removed from the curler. The cold wave solution and neutralizer is quickly applied to a lock of hair on the curler by merely pressing a wad of cotton saturated with the liquid against the outer end of the curler body.

The curler body sections 7 and 8 are preferably molded from thermosetting or thermoplastic material, but it is apparent that these parts may, if desired, be formed from metal, rubber or other material.

While this invention has been shown in but one form, it is obvious to those skilled in the art that it is not so limited but is susceptible of various changes and modifications without departing from the spirit and scope of the claimed invention.

We claim as our invention:

1. In a hair curler, a body, a set of arms provided on each end of said body, said arms being radially disposed and circumferentially spaced about said body to define an annular recess to receive a wound lock of hair, and a clip to secure a wound lock of hair on said body, said clip being formed from a length of resilient wire bent to provide a plurality of arcuate concentric sections and a pair of resilient fingers, the medial portions of said fingers engaging opposite ends of said body.

2. In a hair curler, a body, a set of arms pro-

vided on each end of said body, said arms being radially disposed and circumferentially spaced about said body to define an annular recess to receive a wound lock of hair, and a clip to secure a wound lock of hair on said body, said clip being formed from a length of resilient wire bent to provide a plurality of arcuate concentric sections and a pair of resilient fingers, the medial portions of said fingers engaging opposite ends of said body, the ends of said body being formed with conical recesses to receive the medial portions of said resilient fingers.

3. In a hair curler, a body, a set of arms provided on each end of said body, said arms being radially disposed and circumferentially spaced about said body to define an annular recess to receive a wound lock of hair, and a clip to secure a wound lock of hair on said body, said clip being formed from a length of resilient wire bent to provide a plurality of arcuate concentric sections and a pair of resilient fingers, the medial portions of said fingers engaging opposite ends of said body, the ends of said body being formed with conical recesses to receive the medial portions of said resilient fingers, said body being formed with circumferentially spaced recesses, and said arms being formed with apertures.

4. In a hair curler, a body, a set of arms provided on each end of said body, said arms being radially disposed and circumferentially spaced about said body to define an annular recess to receive a wound lock of hair, and a clip to secure a wound lock of hair on said body, said clip being formed from a length of resilient wire bent to provide a plurality of arcuate concentric sections co-axial with said body and defining an opening to receive the latter, and a pair of resilient fingers, the medial portions of said fingers engaging opposite ends of said body.
